DESIGN FOR A BABY STROLLER

Sam Saltzman, Iowa City, Iowa

Application April 29, 1943, Serial No. 110,078

Term of patent 3½ years

To all whom it may concern:

Be it known that I, Sam Saltzman, a citizen of the United States of America and resident of Iowa City, in the county of Johnson and State of Iowa, have invented a new, original, and ornamental Design for a Baby Stroller, of which the following is a specification, reference being had to the accompanying drawing, forming a part thereof.

Fig. 1 is a perspective view of a baby stroller embodying my new design.

Fig. 2 is a side elevational view of the same.

Fig. 3 is a front elevational view of the stroller.

Fig. 4 is a top plan view.

I claim:

The ornamental design for a baby stroller, substantially as shown.

SAM SALTZMAN.
